INVENTOR.
Annie E. C. White

BY *Warren D. House*

Her ATTORNEY

UNITED STATES PATENT OFFICE.

ANNIE E. C. WHITE, OF KANSAS CITY, MISSOURI.

TRAY.

Application filed July 19, 1924. Serial No. 726,981.

My invention relates to improvements in trays. It is particularly well adapted for use in connection with medicine trays used in hospitals.

5 One of the objects of my invention is to provide novel means for holding tumblers and the like, and novel means for identifying the contents of said tumblers.

A further object of my invention is to provide novel means by which tumblers held on the tray are adapted to hold identifying slips carried on the tray respectively adjacent to the tumblers from accidental removal from their respective identifying positions.

10 My invention provides further novel means for holding the identifying slips from accidental detachment from the tray, when the latter is vertically disposed and is not supporting tumblers.

15 Still another object of my invention is to provide a tray of the kind described, which is simple, sanitary, cheap, durable, not liable to get out of order, and which may be disposed in compact form so as to occupy relatively small space.

The novel features of my invention are hereinafter fully described and claimed.

20 In the accompanying drawing which illustrates the preferred embodiment of my invention,

Fig. 1 is a plan view, partly broken away, of my improved tray having mounted thereon two tumblers and three identifying slips.

25 Fig. 2 is a sectional view on the line 2—2 of Fig. 1.

Fig. 3 is an enlarged sectional view on the line 3—3 of Fig. 1.

Similar reference characters designate similar parts in the different views.

30 The tray is provided with a base member, which may be a flat board 1 having in its upper side a series of transverse rows of holes 2 adapted to respectively receive tumblers or similar devices 3, which may contain medicine for different patients. For identifying the tumblers which are to be delivered to the different patients, suitably inscribed slips 4 may be provided.

35 For respectively holding the slips 4 respectively adjacent to the holes 2, suitable means may be provided. For this purpose, I have provided transversely disposed strips 5, preferably of metal, such as aluminum or brass,

50 which are fastened to the upper side of the

board 1 respectively adjacent to and parallel with the transverse rows of holes 2.

Each strip 5 is provided with a plurality of slip holders having slip receiving openings 6 in the edge of the strip next to the adjacent row of holes 2. Each strip has observation openings 7 respectively registering with the slips 4 through which the inscriptions on the slips may be read. Each strip 5 is also provided with lips 8 adapted to 65 respectively overlap the slips 4 when the latter are in operative position in their respective holders.

The strips 5 are so located with respect to the holes 2 and the width of the slips 4 70 that the tumblers 3, when in the holes 2, will be in the paths respectively traversed by the slips 4 in their insertion or removal through the openings 6. By means of this construction, the tumblers 3 when in the holes 2 will be adapted to respectively engage and hold the identifying slips 4 from accidental removal from their respective holders.

75 For suspending the tray vertically, when not in use, the board 1 at one end has fastened to it suitable supporting or suspending means, which may comprise a plate 9 having a hole 10 adapted to receive a supporting device, such as a nail or screw not shown.

80 The openings 6 are disposed so as to face toward the end of the board 1 having attached to it the plate 9, by means of this construction, when the tray is not in use, and is suspended by the plate 9, and the 85 tumblers are removed, the slips 4 will be retained in their respective holders and can not fall out.

80 Edge strips 11 may be respectively attached to the edges of the board 1, and may project above the top of the board, to hold liquid which may be spilled from the tumblers running off from the board.

95 For carrying the tray, there may be provided two U-shaped handles 12 and 13, the arms of which are respectively pivoted to ears 14 two pairs of which are respectively secured to opposite longitudinal edges of the board 1.

100 In the operation of the invention, the suitably inscribed slips 4 are first mounted in their respective holders, after which the tumblers containing the different medicines are mounted in the proper holes 2 respectively 105 alining with the slips 4 respectively relat-

ing to the tumblers. The latter when in the holes 2 will obstruct the outward passage of the slips 4, thus preventing the accidental removal of the latter.

5 After the tumblers have been removed, the tray may be suspended by the plate 9, and in the vertical position of the tray, the openings 6 will face upwardly, thus preventing the slips 4, which may be left there-
10 in from falling out of their holders.

I do not limit my invention to the structure shown and described, as many modifications, within the scope of the appended claims, may be made without departing from
15 the spirit of my invention.

What I claim is:—

1. In a tray of the kind described, a base member having means for holding tumblers, and a plurality of slip holders adapted to
20 hold removable identifying slips and mount-

ed on said member, the tumblers when held by said holding means being in the paths respectively traversed by said slips in their insertion into and removal from said holders and adapted to respectively engage and hold said slips from accidental detachment from said slip holders.
25

2. In a tray of the kind described, a base board having in its upper side holes adapted to respectively receive tumblers, and means
30 on said base board adapted to receive and hold removable identifying slips respectively adjacent to said holes, tumblers when so held being respectively in the paths traversed by said slips respectively in their insertion or removal with respect to said slip holding means.
35

In testimony whereof I have signed my name to this specification.

ANNIE E. C. WHITE.
